BARREL KEY CUTTING MACHINE

Ludger J. Caron, Leominster, Mass., assignor to
Independent Lock Company, Fitchburg, Mass.,
a corporation of Massachusetts

Application June 13, 1934, Serial No. 730,527

10 Claims. (Cl. 90—13.05)

This invention relates to a machine for cutting barrel keys.

The principal objects of the invention are to provide means by which a key blank of the barrel type can be made efficiently and expeditiously from a completed key; to provide a gauge which will indicate automatically the depth of the cut on a cut key and an adjustable stop that can be set in accordance with said gauge so that the cutting tool and key blank will be brought together just far enough to cut the blank to that depth; to provide a holder for the key blank rotatable on the axis of the blank to allow the key blank to be turned on its own axis a series of steps equal to the number of possible cuts on the key and properly spaced, in combination with a cutter, set eccentrically with regard to the axis of the key blank for cutting into the edge of the barrel shaped blank, and to provide these parts so related as to constitute a neat and compact machine, easy to operate and having few parts likely to get out of order.

Other objects and advantages of the invention will appear hereinafter.

Reference is to be had to the accompanying drawings, in which

Fig. 1 is a side elevation of a machine constructed in accordance with this invention;

Fig. 2 is a plan of the same;

Fig. 3 is a plan of a barrel key cut on this machine;

Fig. 4 is an end view of the same showing the position of the rotating cutting tool with respect thereto when making one of the cuts;

Fig. 5 is an end view of the blank holding part of the machine looking from the cutter end of the machine, as indicated by the section line 5—5 of Fig. 1;

Fig. 6 is a sectional view on the line 6—6 of Fig. 1;

Fig. 7 is a plan of the cutting and blank holding part of the machine;

Fig. 8 is a plan of the indicating part of the machine with parts in section, and

Fig. 9 is a horizontal sectional view showing the pin on which the transversely cut key is applied for determining the cuts on the blank.

This machine in the form in which it is illustrated is designed for the cutting of a barrel type of key used with barrel locks, although some of the features of the invention can be applied to the flat type of key. This is an old type of lock and key and this invention relates only to the cutting of the key. Of course, the barrel key consists of a tube square on the end, the cuts being

made on the circumference of the tube and being of course of different depths.

The key also has a radial projection 12 for guiding it into the proper position in the lock as it has to be located circumferentially in order to fit the lock.

The machine is shown as provided with a base 13 having two standards 14 and 15, preferably integral with it and extending up from it centrally. On the standard 14 are located bearings in which is rotatably mounted a spindle 16 having a pulley 17 for operation by a belt 18 or it can be operated in any other desired way. On the other end of the spindle is a chuck or other tool holder 19 for receiving centrally a cutting tool 20 in the form of a flat ended drill. This constitutes the entire cutting apparatus.

On the standard 15 are located bearings spaced apart for a shaft 22. There is a space between the two bearings for this shaft and within that space is located a spring 23 bearing against a collar 24 fixed on the shaft and forcing the shaft back until the collar engages the solid part of the frame. An operating handle 25 is shown having a pin 26 engaging the end of the shaft for moving the shaft forward.

On the shaft at its opposite end is integrally mounted an indicating hub 27 having a series of notches 28 on its circumference for receiving a spring-pressed stop 29. These notches are cut with a slant in one direction so that this hub can be rotated step by step but in one direction only. On the frame is an arrow 30 indicating the zero point and on the hub is a second arrow 31 indicating the starting point, as will appear.

Projecting from the hub 27 is a longitudinal bar 38 preferably integral with the hub and having a transverse end 32 provided with a diametrical slit 33 and a fixed pointer 34. A screw 35 is located at one end of this slot for tightening it up and there is a central recess 36 for receiving a key blank set in from the back, as shown. There is also a radial notch 37 for receiving the outer projection 12 of the undercut key blank so that this blank is positively fixed with respect to the notched hub 27. After the blank is inserted, it can be fastened by tightening up the screw 35.

The axis of the shaft 22 and of the key blank is offset from the axis of the spindle 16 and the cutting tool 20 just enough so that the edge of the cutting tool will cut into the edge of the blank. The key blank turns on its own axis by the rotation by hand of the hub 27 to bring it into position for the cutter, which is mounted on

a stationary axis, to make the desired cuts around the circumference.

It will be understood that the cutting operation is performed by pressing on the handle 25 and forcing the whole structure carried by the shaft 22 toward the constantly rotating cutter 20. When one cut has been performed the handle is released, the spring pulls the shaft back and then the hub 27 is turned another notch and the 10 operation repeated in a different place around the circumference of the key blank.

The machine is provided with an adjustable stop. This consists of a fixed screw 40 on the standard 15 and the stop in the form of a disc 41 having a starting mark 42 and a series of numerals equally spaced. On the integral member 43 of the standard 15 is mounted a stationary pointer 44. As this disc is threadedly engaged with the screw 40 it will move forward and back in accordance with the numerals on its circumference and it is located in such a position that the hub 27 engages it when the handle 25 is pushed inwardly. This limits the motion of the shaft and the key blank in accordance with the position of the disc 41 on its screw.

In order to provide a simple and effective means for showing where the stop disc 41 should be placed, that is, what numeral thereon should be placed in registration with the pointer 44, a gauging device is provided. This consists of a pin 46, mounted on the head of the standard 14 and preferably on the top thereof, this pin fitting the interior of the barrel key that has been cut and provided with a longitudinal slot 47 for receiving the projection 12. This pin is provided with a circumferential groove 48 and is set into an opening through the top of the standard 14 which fits the pin. A set screw 49 is inserted to hold the pin in a fixed position, longitudinally, but it is capable of being turned on its own axis on account of the set screw setting into the groove 48 but not restricting the rotation of the pin.

Above the pin 46 are located two spring pressed reciprocable pins 50 and 51, in alignment, the pin 50 projecting over the pin 46 and parallel to it. The spring normally forces these pins outwardly. Between these pins is a space into which projects the end of an indicating needle 52, which is pivoted on an axis 53 at the side. The indicating end of the needle 52 moves over a scale 54 provided with numerals.

In operation a key, already cut, is placed on the pin 46 and it can be placed in only one position thereon because of the groove 47 and projection 12. It is turned, with this pin 46, until one of the cuts registers with the pin 50. Then it is pushed in until the end of the key engages the surface of the supporting part in which the pin 46 is located. This pushes in the pin 50 a distance controlled by the depth of the cut on the key. The result is that the pointer 52 moves along the scale 54 and in the instance shown, indicates that the depth of the cut is 4. The stop disc 41 is turned until the numeral 4 thereon registers with the pointer 44 and that fixes this stop disc so that when the handle 25 is moved to push up the shaft 22, it can be moved only so far as to allow the cutter 20 to cut into the key blank 10 a distance indicated by the numeral 4. In other words, it is a number 4 cut.

When this cut has been completed by this means the handle 25 is released, the shaft 22, moves back, and the operator pulls the cut key 75 out along the pin 46 and turns it through one

space and then presses it back to move the pointer 52 to a different position. Then the hub 27 is moved through one space to turn the key blank for the next cut. The stop disc 41 is then turned to agree with the numeral on the scale 54 and the handle 25 is moved up to perform the second cut.

This constitutes a very simple way of operating to reduce the desired and necessary cuts on a key blank and the machine is simple and easily operated.

Having thus described my invention and the advantages thereof, I do not wish to be limited to the details herein disclosed, otherwise than as set forth in the claims, but what I claim is:—

1. In a machine for cutting barrel key blanks, the combination of a rotary work spindle having a cutting tool, a shaft arranged eccentrically with respect to the spindle but on a parallel axis and located entirely beyond the end of the work 35 spindle, means carried by said shaft for holding the blank to be cut in such position that the cutting tool will cut an arc on the edge of the blank, and means for moving the shaft toward the work spindle and into such position that the tool will 100 cut into the edge of the blank.

2. In a machine for cutting keys of the barrel type, the combination with a work spindle and a cutter thereon, said spindle being rotatable on its own axis, of a shaft located on an axis parallel with said axis and beyond the tool, means integrally mounted on the shaft to hold the blank to be cut, the shaft being rotatable on its axis, and means by which the shaft can be turned through an arc equal to the arc between two cuts 110 to be made on the blank.

3. In a machine for cutting keys of the barrel type, the combination with a work spindle and a cutter thereon, said spindle being rotatable on its own axis, of a shaft located on an axis 115 parallel with said axis and beyond the tool, means integrally mounted on the shaft to hold the blank to be cut, the shaft being rotatable on its axis, means by which the shaft can be turned through an arc equal to the arc between two cuts to be 120 made on the blank, a spring for holding the shaft back in inoperative position, and a lever having a projection for engaging the end of the shaft, whereby the motion of the lever will move the shaft up to cutting position.

4. In a machine for cutting barrel key blanks, the combination of a rotary spindle having a cutting tool on the end thereof, with a rotatable and longitudinally movable shaft, a holder on the shaft for the cutting blank arranged in position to locate the key blank in a position eccentric with respect to the spindle, a disc on the shaft by which it can be turned by hand, and a spring stop for the disc, said disc having notches for engaging the spring stop in a plurality of predetermined positions, and of a shape to prevent the disc and shaft from being rotated backwardly.

5. In a machine for cutting barrel type key blanks, the combination with a rotary spindle and a cutting tool carried at its end, of a shaft 140 located entirely beyond the cutting tool, said shaft having an integral holder for the key blank thereon, and a disc on the shaft by which the shaft can be turned to different positions to bring the key blank into proper position for cutting, the 145 shaft being provided with a wide space between the key holder and the disc, for the purpose described.

6. In a machine for cutting barrel key blanks, the combination of a rotary spindle having a cut- 150

ting tool, a shaft arranged eccentrically with respect to the spindle but on a parallel axis and located entirely beyond the end of the work spindle, means carried by said shaft for holding the blank to be cut in such position that the cutting tool will cut an arc on the edge of the blank, means for moving the shaft toward the work spindle and into such position that the tool will cut into the edge of the blank, and an adjustable stop in position to prevent the motion of the shaft toward the spindle in the proper place to enable the tool to cut the key to the desired depth.

7. In a machine for cutting barrel key blanks, the combination of a rotary spindle having a cutting tool on the end thereof with a rotatable and longitudinally movable shaft, a holder on the shaft for the cutting blank arranged in position to locate the key blank in a position eccentric with respect to the spindle, a disc on the shaft by which it can be turned by hand, a spring stop for the disc, said disc having notches for engaging the spring stop in a plurality of predetermined positions, and of a shape to prevent the disc and shaft from being rotated backwardly, a stationary screw, a stop disc threaded on said screw, whereby the turning of the stop disc will effect its adjustment along the screw, and means on the shaft for engaging the stop disc to limit the motion of the shaft toward the tool for the purpose described.

8. In a machine for cutting barrel key blanks, the combination with a spindle and a cutting tool mounted on the end thereof, of a shaft reciprocable toward and from the cutting tool and mounted eccentrically with respect to the spindle, means

on the shaft for holding the key blank, a gauge for receiving a previously cut key having a pointer, a scale adapted to indicate with the pointer the depths of the cuts on the key, a longitudinally adjustable stop disc having numerals thereon corresponding with the numerals on the scale, and a pointer cooperating with the stop disc whereby, when the stop disc is set at the same number relative to said pointer that appears on the scale, the stop disc will stop the shaft from being moved beyond the point at which the cutter will cut the blank to the same depth as the key.

9. In a machine for cutting barrel key blanks, the combination with a spindle and a cutting tool mounted on the end thereof, of a shaft reciprocable toward and from the cutting tool and mounted eccentrically with respect to the spindle, means on the shaft for holding the key blank, a gauge for receiving a previously cut key having a pointer, and a scale adapted to indicate with the pointer the depths of the cuts on the key.

10. In a gauge for a key cutting machine, the combination of a pin on which a previously cut barrel key is adapted to be mounted, said pin having means for causing it to turn on its axis when the key is turned, a spring pressed pin above the first named pin and parallel therewith at such a distance from the first pin that the second pin will enter the cuts in the end of a barrel key placed on the first pin, a pivoted pointer, and a scale, said pointer being connected with the second pin to be moved thereby when the cut key is pressed in to indicate the depth of the cut on the scale.
